UNITED STATES PATENT OFFICE.

THOMAS WATSON AND CHRISTOPHER FREDERICK WEBB, OF KENTISH TOWN,
LONDON, ENGLAND.

CLOCK MECHANISM.

1,368,004.

Specification of Letters Patent.

Patented Feb. 8, 1921.

Application filed June 7, 1920. Serial No. 387,008.

To all whom it may concern:

Be it known that we, THOMAS WATSON and CHRISTOPHER FREDERICK WEBB, both subjects of the King of Great Britain and 5 Ireland, and both residing at Falkland Works, Falkland Road, Kentish Town, London, N. W. 5, England, have invented certain new and useful Improvements in Clock Mechanisms, of which the following 10 is a specification.

This invention relates to clock mechanisms and has for its object to provide a simple and reliable clock which will be self-adjusting for reasonable variations in level, 15 will require little or no lubrication, and will have the wearing parts and the degree of wear to which such parts are subject reduced to a minimum.

The invention consists in a clock in which 20 the balance member is carried by a pivot or pivots adapted to roll relatively to the bearing or bearings for such pivot or pivots.

The invention also consists in a clock of the above character in which the balance 25 member carries the pallets.

The invention also consists in a clock of the above character in which the track on which the pivot rolls is curved or arcuate.

The invention also consists in other details and arrangements hereinafter more particularly referred to.

The accompanying drawings illustrate several modes of carrying out the invention.

35 Figure 1 is a front elevation of the escapement wheel on an enlarged scale showing the pallets and a portion of a vertical balance arm and the means of supporting same.

Fig. 2 is a part sectional side elevation 40 of Fig. 1.

Fig. 3 is a front elevation on an enlarged scale showing a modified arrangement of mechanism such as is shown in Fig. 1.

Fig. 4 is a part sectional side elevation of 45 Fig. 3.

Fig. 5 is a front elevation showing in diagrammatic form the complete vertical form of balance arm in relation to the escapement.

Fig. 6 is a front elevation showing diagrammatically the horizontal balance arm arrangement shown in Fig. 3.

Fig. 7 is a front elevation in diagrammatic form of a clock mechanism and case arranged in accordance with the invention.

Fig. 8 is a plan of Fig. 7 with the case in 55 section and having some of the superimposed parts omitted for clearness.

Fig. 9 is a front elevation of part of the escapement wheel, pallets, pivot and balance arm intended to show the action of the es- 60 capement.

In carrying the invention into effect in one convenient manner as illustrated, for example, in Figs. 1 and 2, the balance rod *a* of steel or other material is supported vertically at or about the middle by a pivot or pivots *b* *c* and carries at each end a balance weight *o* (Fig. 5).

The pivot or pivots roll upon a suitable support which is slotted or recessed and 70 the balance arm has fixed thereto or combined therewith the escapement pallets *d* *e* which are preferably of the dead beat form.

The escape wheel *f* is so arranged that part of the support on which the balance rests is 75 curved preferably to an arc of a circle struck from the center of the escape wheel so that the balance rod and pallets automatically adjust themselves to any reasonable variation of the clock level. The escape 80 wheel may be above or below the pallets or in any intermediate position, and the period of vibration may be arranged for half-second, one second, or any other interval without any alteration in size or construction 85 by merely changing the position of the weights in relation to the center of balance. The balance may, therefore, be conveniently arranged to swing once per second and the escape wheel to contain 30 teeth and rotate 90 once per minute, so that with this arrangement a second's hand can be fitted to the escape wheel arbor and will indicate true seconds without intermediate jumps or positions which is for many purposes a great 95 advantage over other known forms of clock in which this feature is absent.

In the form shown in Figs. 1 and 2 the pivots *b* *c* roll in holes or slots *g* formed both in the movement plate *h* and in a 100 bridge-plate *i* and the operation of the escapement wheel balance arm and pallets will be clear from a study of Fig. 9 of the drawings in which α which is the angle between the vertical and the axis of the balance arm 105 in its extreme position is half the total swing of the pendulum assuming that there is no dwell of the escapement wheel.

In the position shown the tooth e' is about to press on the pallet e to cause the pendulum to swing to the left and the pivot c to roll to the right and by the time the tooth e' escapes from the pallet e the tooth d' will be just in contact with the pallet d so that it will then act thereon to cause the pendulum to swing to the right and the pivot c to roll to the left.

10 In place of arranging the balance arm when at rest it may be disposed to be horizontal and one convenient method of effecting this is shown in Figs. 3, 4 and 6 where the balance arm a with its pallets d e is 15 carried by a stirrup or bracket h suspended by a boss l around the pivot of the escape wheel f and from a bridge-plate m . It will be obvious, however, that the stirrup attachment such as is employed for the horizontal balance arm may be modified to suit 20 the vertical form of balance.

In any modification of the invention the balance arm is adapted to carry weights o and adjustment for timing may be readily 25 effected by varying the perpendicular distance of the center of gravity of the weights from the axis of suspension. Thus, in the vertical form shown in Fig. 5 the adjustment may be effected by moving the weights 30 or one or other of them along the balance arm while in the horizontal form the adjustment may conveniently be effected by mounting the weights o eccentrically on the balance arm which may be rotated within 35 the block n to effect the required adjustments.

The vertical form of arm may be looped at p (Fig. 5) in order to pass the center spindle q of the clock movement when the 40 balance arm is arranged in front of the movement, and another loop may be formed to pass the spindle of the escape wheel f if it is desired to fit a second's indicator.

The line X—Y in Fig. 6 passing through 45 the center of the escape wheel f and the center spindle q indicates how the vertical axis of the clock may be tilted to a considerable extent and yet allow the pivot c of the balance arm to remain directly beneath 50 the center of the escape wheel while at the same time keeping the pallets in correct relation to the wheel tooth.

With the pivots of the balance arm rolling in the curved race or slot no lubrication 55 is required, and the pallets if attached to the balance require no other pivots and are free from the wear and other objections which are always associated with pivots working in inclosed holes and requiring 60 lubrication.

It is a further advantage that a timepiece fitted with this form of balance does not require additional and delicate parts necessary where quick moving pendulum or 65 standard form of balance is used and is con-

sequently simple and inexpensive to manufacture while at the same time being exceedingly silent in operation.

Further, it requires much less driving power than quickly moving wheels and 70 pivots with the result that much of the strain and wear is eliminated so that greater reliability and longer life is assured for the mechanism.

The curve of the recess can be so arranged 75 that the rolling motion of the pivots to right or left of the vertical causes every point of the weighted and compound arc to describe a hypocycloidal arc instead of a circular arc as in ordinary escapements, but 80 it is clear that by making the radius of the circle on which the pivot rolls very great the hypocycloid will approximate to a true cycloid and the oscillations will become 85 truly isochronous.

The invention is applicable to many types of clocks and timepieces and is particularly applicable to that form in which the weight of the entire clock movement is used to provide the necessary energy for driving the 90 mechanism. This latter form of clock is illustrated in Figs. 7 and 8 in which the case r carrying the frame s of the movement is free to slide on the pillars or guides t t' , the latter being cut in the form of a 95 rack adapted gear with the driving pinion u of the wheel train.

The motion of the pinion u in rolling down the rack transmits movement to the escape wheel f in the usual way through the 100 wheels v w x and the pinions 1, 2, 3.

In order to facilitate economical manufacture the wheels v , w , x are alike in diameter and pitch containing, say, 60 teeth, while the pinions u , 1 and 2, are also alike 105 containing, say 10 teeth. In such case the pinion 3 contains 6 teeth and revolves once per minute, while the escape wheel f contains 30 teeth for second's control.

Provision for the differences in driving 110 pressure may be made by varying the thickness of the wheels v , w , x .

For the purpose of raising the clock which is equivalent to the action of winding the pinion u and the wheel v are separately formed and normally move together 115 by means of a clutch 4, maintained in action by a spring 5.

Either the wheel or the pinion is free to slide on its spindle thus allowing the pinion 120 to rotate in one direction independently of the wheel train.

The hands of the clock are shown independently of their spindles at 6 and 7, while the usual motion wheels for driving 125 the hour hand are also omitted. When arranged as described with the balance arm in front of the movement a plate, 8, may conveniently be used to cover the movement and a ring dial, 9, employed.

It will be understood that the foregoing details of construction are given by way of example only, as it will be clear that I may modify the form and arrangement of 5 slot or track on or in which the pivot or pivots roll, the form of wheel train employed, the means for imparting the necessary energy to the mechanism and the details of construction relative to the balance 10 arm, pallets and escape wheel, all as may be determined by the type or construction of clock to which the invention is to be applied or any particular practical requirements that may have to be fulfilled.

15 Having now particularly described and ascertained the nature of our said invention and in what manner the same is to be performed, we declare that what we claim is:—

1. A clock in which the balance member 20 is carried by a pivot or pivots adapted to roll relatively to the bearing or bearings for such pivot or pivots.

2. A clock as claimed in claim 1, in which the balance member carries the pallets.

25 3. A clock as claimed in claim 1, in which the track on which the pivot rolls is curved or arcuate.

4. A clock as claimed in claim 1, in which the balance member is carried by a stirrup 30 supported by a pivot or pivots adapted to

roll relatively to the bearing or bearings supporting said pivot or pivots.

5. A clock in which the compound or other pendulum carries pallets and pivots which roll in a curved slot or upon a curved 35 track.

6. A clock as claimed in claim 3, in which the curve on which the pivot rolls is an arc of a circle struck from the center of the escapement wheel. 40

7. A clock as claimed in claim 1, in which the balance member consists of a balance arm carrying weights upon either side of the point of suspension and suitably supported. 45

8. A clock as claimed in claim 7, in which the adjustment for timing is made by altering the perpendicular distance of the center of gravity of the weights from the axis of suspension. 50

9. A clock in which the compound or other pendulum carries pallets and pivots which roll on a curved track forming an arc of a circle struck from the center of the escapement wheel. 55

In testimony whereof we have signed our names to this specification.

THOMAS WATSON.

CHRISTOPHER FREDERICK WEBB.
